UNITED STATES PATENT OFFICE.

HARRY C. COLE, OF PHILADELPHIA, PENNSYLVANIA.

SPRAY CONTROL FOR PRINTING PRESSES.

Application filed July 7, 1928. Serial No. 290,934.

In certain lines of printing and colored lithographing work it has been the practice to spray the sheet after the lithographing, coloring or printing has been effected before 5 piling or folding with a very thin film of paraffine electrically heated to a liquid, said film of paraffine having heretofore been sprayed over the entire area of the printed sheet clear to the edges thereof. While the 10 liquid paraffine deposited on the printed sheet or web is usually considered as a film, it is in reality deposited as innumerable, minute wax particles which are chilled before coming in contact with the paper, their 15 action being mechanical and serving to hold the sheets apart while the ink is drying.

The object of my present invention is to provide a novel attachment, whereby the paraffine is deposited solely upon the lithographed, colored or printed area, which I effect by means of one or more endless aprons positioned in proximity to the printed sheet or web, said aprons having cut-out portions which register exactly with the printed, 25 lithographed or colored areas, while the solid portions at the edges and intermediate portions of said aprons prevent the paraffine from being deposited upon or being applied at points where it is not desired or necessary.

To the above ends, my invention consists of one or more endless aprons having cut-out portions arranged in proximity to or above and below the printed sheet or web, 35 there being upwardly and downwardly spraying nozzles arranged within the aprons above and below the printed sheet or web in conjunction with brushes or scraping devices which are positioned so as to contact 40 with the contiguous surfaces of the aprons while scraping the surplus paraffine therefrom so that it can be saved and used over again.

By my novel construction, means are provided whereby the spray or sprays of paraffine are confined solely to the printed or lithographed area of a printed sheet where it is needed, and said spray is further kept away from the edges or margins of the 50 sprayed sheet and the intermediate blank portions thereof.

My invention consists of a novel method of spraying and other novel features of construction and advantage all hereinafter de-

scribed and claimed in the claims appended 55 hereto.

Referring to the drawings:

Figure 1 represents a perspective view of a novel spray control for printing presses and the like, embodying my invention. 60

Figure 2 represents a section on line 2—2, Figure 1.

Figure 3 represents on an enlarged scale a vertical sectional view of the upper nozzle seen in Figures 1 and 2. 65

Figure 4 represents, on an enlarged scale, a vertical sectional view of the lower nozzle seen in Figures 1 and 2.

Figure 5 represents, on an enlarged scale, a section on line 5—5 of Figure 1, showing 70 an upper brush for removing the paraffine from the underside of the upper endless apron.

In the drawings, in which like reference characters indicate like parts, 1 designates 75 my novel construction of spray control, which is adapted to be readily installed upon printing presses of any conventional type. In carrying out my invention, I provide the standards or posts 2 in the upper 80 portions of which are provided bearings for the journals 3 of the upper rollers 5 and 6 around which passes the endless belt or apron 7 having the cut-out portions 8 there- 85 in. The rollers 5 and 6 can be revolved or actuated by any suitable means, and in the present instance I have shown the sprocket wheel 9 around which passes the sprocket chain 10 which can be driven from any suitable source of power. In the lower portions 90 of the standards 2 are provided the bearings or journals 11 for the rollers 12 and 13 over which passes the endless apron 14 provided with the cut-out portions 15. The rollers 12 and 13 can be revolved by any 95 suitable mechanism as the sprocket wheel 15 driven by the sprocket chain 16, which is actuated by any suitable source of power.

17 designates the printed sheet or web which is positioned between the upper and lower 100 aprons 7 and 14. The posts 18 serve to support the upper and lower spray nozzles 19 and 20, whose construction will be understood from Figures 3 and 4, respectively.

Any suitable form of nozzles may be employed, and in the present instance I have shown one satisfactory form of nozzle which comprises a bar of aluminum or the like,

21, which extends across the top of the press, carrying the spray nozzles, paraffine supply well and their adjuncts. This bar 21 has a well 24* for the paraffine, an air supply 5 pipe 24, a paraffine delivery wheel 22 and a nozzle 23 for each inch of paper width, said bar being set a few inches above the traveling paper.

The paraffine being electrically heated to 10 a liquid in any suitable manner is introduced into the well 24* and air is introduced through the pipe 24 into the passage 25 which is controlled by the valve 26 and the liquid paraffine emerges at the point 27 under pressure in the form of a fine spray, 15 which is deflected downwardly as will be understood from Figure 3 and the upper portions of Figures 1 and 2.

The lower spray nozzle 20 is similarly constructed, being provided with the well 24* for the liquid paraffine while compressed air flows into the passage 25 controlled by the valve 26 and is forced outwardly so as to have its exit at the point 28 so that a spray is discharged upwardly, as will be understood from Figures 1, 2 and 4.

As the details of the upper and lower nozzles form, per se, no part of my invention, I deem it unnecessary to describe the same 30 in further detail, as any suitable form of spraying nozzle may be employed.

It will be understood from Figure 1 that the portions or areas, as 29, designate the printed, colored or lithographed areas on the printed sheet or web 17 and the cut-out portions 8 of the endless apron 7 accurately register or align therewith, the purpose of the lower apron being the same so that said upper and lower endless bands or aprons 35 function somewhat as a stencil or template, in that the uncut portion of said aprons including the marginal portions 30, the transversely uncut portions 31 and the longitudinal central uncut portions as 32, prevent the paraffine spray from being deposited upon the printed or lithographed web 17, at places where it is not desired. The paraffine which is deposited on the inner surfaces of the upper and lower aprons is removed therefrom 40 by means of the brushes 33, one of the upper brushes being shown in Figure 5 as being supported upon the spring 34 through which the stem 35 passes, said stem being mounted in the partition 36.

55 The lower end of the spring 34 bears on the partition 36 and the upper end on the head 37 of the brush, so that the brush is at all times in contact with the under surfaces 38 of the upper apron, any surplus paraffine being removed and deposited in the receptacle 39.

The construction seen in Figure 5 is applicable to the upper apron and the construction for cleaning the inner surface of

the lower apron is substantially the same as will be understood from the lower right hand portion of Figure 2.

The operation is as follows:—The printed sheet or web 17 is fed to the apparatus above 70 described between the aprons 7 and 14 in the direction of the arrows seen in Figures 1 and 2, said sheet being ordinarily printed on both sides, so that when said aprons are actuated and the paraffine spray is fed 75 thereupon through the upper and lower nozzles 19 and 20, said spray will be deposited only upon the exposed lithographed, colored or printed areas desired, since the function of the solid portions of said endless aprons 80 is to prevent the paraffine from being indiscriminately sprayed upon all portions of the printed, colored or lithographed sheet, where it is not necessary but solely upon the exposed portion. When the printed web 17 85 and the upper and lower endless aprons are traveling in the direction of the arrows seen in Figure 1, it will be apparent that the paraffine is simultaneously sprayed as previously described upon the desired exposed areas 90 and as the endless aprons continue their travel in the direction of the arrows, their inner surface comes in contact with the brushes 33, which remove all the surplus paraffine from said aprons, and deposit it 95 in the receptacles 39.

It will be seen from the foregoing, that as the paraffine spray is used solely upon the exposed printed areas desired and as any surplus thereof is automatically removed from the endless aprons, there is no waste of paraffine under any conditions and it will be obvious that the above described novel method and apparatus is most efficient and practical and the apparatus employed is very simple in construction and comparatively inexpensive to manufacture.

It is evident that the rollers and the aprons can be actuated by any suitable means other than that shown, it only being necessary that the cut-out portions of the aprons, which are usually rectangular, register or align accurately with the colored, lithographed or printed areas which it is desired the paraffine spray should reach. While I have shown a plurality of apertured aprons, it will be apparent that a single apertured apron may be employed, wherever necessary or expedient.

In printing four-color work on a two color press, the paraffine is applied after the first two colors are printed, and again after the second two colors. No difficulty is experienced in printing the second two colors on 125 top of the first application of paraffine, or in backing the sheet in a like manner.

When paraffine is applied to the web of a perfecting press, printing one or more colors on both sides with flat-sheet delivery, it is 130

necessary to spray one side only to effectively prevent all offset in the pile; but on a perfecting press equipped with folder, where in folding, two pages are brought together from either of the two sides of the web, it is necessary to spray both sides to prevent all offset, and smearing in jogging the signature prior to piling on trucks.

In practice the amount of paraffine being so small, it entirely disappears on subsequent handling of the paper.

It will be understood from the foregoing that with my novel device, there is no waste of paraffine and that I am enabled to reclaim all the paraffine in the solid portions of the endless aprons.

It will be apparent that the sprocket chains 10 and 16 seen at the left of Figure 1 may be driven from any suitable source of power. In practice, I prefer to drive said sprocket chains directly from the press or by means of mechanism which co-acts with the devices which feed the printed web so that I ensure at all times the registering of the apron openings with the printed parts, as 29, of the web 17.

I deem it unnecessary to show or describe the feeding mechanism for the web 17 as my invention is applicable to any conventional type of press.

In order that the upper apron may be positively driven under all conditions, I provide the upper rolls or drums 5 and 6 with spurs, as indicated at 40; said spurs engaging the holes 41 in the margin of the upper apron. In like manner, I provide the lower rolls 12 and 13 with the driving spurs 42 which engage the holes 43 near the marginal edges of the lower apron 14.

It will be apparent that by this construction, there is no liability of the upper and lower aprons slipping under any conditions as the same will be positively driven so that the cut-out portions of the respective aprons

will properly register or align at all times 45 with the printed areas 29.

It will further be apparent that while I have shown the printed web 17 as traveling horizontally the same may stand vertical or travel in a vertical direction or in an inclined direction, as may be desired.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention what I claim as new and desire to secure by Letters Patent, is:—

1. A machine for spraying a printed paper web, comprising two pairs of driven rollers, 65 an endless apron passed around each pair so that their inner plies run in close proximity to each other, the web being interposed between said plies, each apron having openings corresponding to the portions of the 70 web to be sprayed, spraying nozzles mounted between the plies of each apron so as to spray both sides of the web, and means to remove the substance sprayed onto the aprons around the openings therein.

2. A machine for spraying paraffine onto a printed, colored or lithographed paper web, comprising two superposed endless aprons having cut out portions, means to drive said aprons with the web between the 80 adjacent plies thereof, nozzles between the plies of each apron arranged to spray paraffine onto both sides of the web through the cut out portions of the aprons, and yielding brushes mounted between the plies of each 85 apron to remove excess paraffine from the uncut out portions thereof.

HARRY C. COLE.
